(57) **CLAIM**

The ornamental design for a fishing lure, as shown and described.

DESCRIPTION

FIG. 1 is a front view of my new design for a fishing lure; FIG. 2 is a rear view of my new design for a fishing lure; FIG. 3 is a right side view thereof and wherein the attractor blade exhibits a hammered appearance over the entire exposed surface but only a portion of which is shown; and FIG. 4 is a left side view thereof.

FIG. 5 is a right side view of an alternative design of my lure wherein the front and rear views are identical to FIGS. 1 and 2 and wherein the attractor blade exhibits a hammered appearance over the entire exposed surface but only a portion of which is shown; and, FIG. 6 is a left side view of the alternative embodiment.
